(57) **CLAIM**

The ornamental design for a mirror, as shown and described.

DESCRIPTION

FIG. 1 is a rear, right, bottom perspective view of a first embodiment of a mirror showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a rear, left, bottom perspective view of a second embodiment of the mirror;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

A third embodiment of the claimed design for the mirror is a mirror image of the mirror as shown in FIGS. 1 to 7. Similarly, a fourth embodiment of the claimed design for the mirror is a mirror image of the mirror as shown in FIGS. 8 to 14.
